(57) **CLAIM**

The ornamental design for a cartridge body for solid-phase extraction, as shown and described.

DESCRIPTION

FIG. 1 is a perspective view of the cartridge body for solid-phase extraction showing my new design;

FIG. 2 is a front view thereof;

FIG. 3 is a back view thereof;

FIG. 4 is a right side view thereof;

FIG. 5 is a left side elevational view thereof;

FIG. 6 is a plan view thereof;

FIG. 7 is a bottom view thereof;

FIG. 8 is a view taken along lines VIII-VIII of FIG. 6;

FIG. 9 is a cross-sectional view taken along lines VIII-VIII of FIG. 6 showing a state of use with an unclaimed environmental upper and lower frits and solid phase filling material;

FIG. 10 is a cross-sectional view taken along lines VIII-VIII of FIG. 6 showing a state of use with an unclaimed environmental upper and lower frits, upper and lower plungers and solid phase filling material;

FIG. 11 is a cross-sectional view taken along lines VIII-VIII of FIG. 6 showing another state of use with an unclaimed environmental partial cartridge body for solid-phase extraction, upper and lower frits, lower plunger and solid phase filling material; and,

FIG. 12 is a cross-sectional view taken along lines VIII-VIII of FIG. 6 showing a further state of use with an unclaimed environmental cartridge body for solid-phase extraction, upper and lower frits and solid phase filling material.

The broken lines are included for the purpose of illustrating unclaimed environmental subject matter used with the translucent cartridge body for solid-phase extraction and form no part of the claimed design.

1 Claim, 12 Drawing Sheets
